CLAIM

I claim the ornamental design for a battery, as shown and described.

DESCRIPTION

FIG. 1 is a top left perspective view of a battery showing my new design;

FIG. 2 is a bottom right perspective view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a front elevation view thereof; and

FIG. 8 is a rear elevation view thereof.

FIG. 9 is a top left perspective view of a battery showing my new design;

FIG. 10 is a bottom right perspective view thereof;

FIG. 11 is a left side elevation view thereof;

FIG. 12 is a right side elevation view thereof;

FIG. 13 is a top plan view thereof;

FIG. 14 is a bottom plan view thereof;

FIG. 15 is a front elevation view thereof; and,

FIG. 16 is a rear elevation view thereof.

1 Claim, 14 Drawing Sheets
